PROPELLER AUXILIARY POWER CONTROL

Chester M. Jedrzwieski, Rockville, Conn., assignor to United Aircraft Corporation, East Hartford, Conn., a corporation of Delaware

Application September 2, 1953, Serial No. 378,096

19 Claims. (Cl. 170—160.2)

This invention relates to improved propeller control mechanism and particularly to an improved power supply system for power actuated pitch control mechanism.

An object of this invention is a light and efficient fluid supply system for a hydraulically actuated propeller.

A further object is mechanism by which a pump of small capacity is utilized for normal pitch changes and an auxiliary pump is automatically connected in parallel with said small pump for larger or more rapid pitch changes.

A still further object is mechanism under the control of the governor for increasing the volume of fluid supply when the governor reaches a predetermined off speed position.

A further object is the provision, in a governor having contacts closable by movement of the governor to supply governing power, of means for supplying governor power while the contacts are open.

A still further object is an improved propeller governing system.

Other objects and advantages will be apparent from the specification and claims, and from the accompanying drawings which illustrate what is now considered to be the preferred embodiment of the invention.

Fig. 1 is a somewhat schematic end view of the propeller control mechanism including a schematic wiring diagram.

Fig. 2 is a schematic side view showing the hydraulic control mechanism and the pitch changing mechanism.

Fig. 3 is a partial wiring diagram illustrating how the wiring diagram of Fig. 1 may be changed for operation of the governor switch in both directions.

In the drawings which illustrate a mechanical construction which is now considered the preferred form of the invention, a propeller of the type shown in application 84,305, filed March 30, 1949, by John E. Anderson is utilized. Reference may be made to that application for a more complete description of the propeller and its control. In general the propeller comprises a control unit indicated generally at 10 rotatably supported on bearings on the propeller unit indicated generally at 12. The control unit 10 includes a bearing sleeve 14 which is telescoped with and supported on an axial projection 16 on the hub 18 of the propeller 12. The sleeve 14 is secured in position on the hub and held against axial or rotational movement thereon, as more fully described in the above-mentioned application.

The propeller may be of any type utilizing hydraulic fluid for pitch changing and preferably having the propeller pitch changing motor carried by and rotating with the propeller. In the preferred form, the pitch changing motor comprises a piston mounted in a cylinder 34 and by means of cam slots 36 and cam rollers, not shown, turns a connecting gear 38 geared to the propeller blades 40 to thereby change the propeller blade pitch. Oil may be selectively directed to either side of the pitch changing mechanism by means of conduits 42 and 44. The propeller is secured to a propeller or engine shaft

2

46 supported in the usual manner by bearings in the engine 190 or engine nose. For further details of these propeller constructions, reference may be made to Patent No. 2,477,868 of George W. Forman, filed April 17, 1946, and issued August 2, 1949. Reference may also be made to Patent No. 2,371,873 of Erle Martin, issued March 20, 1945, for a further disclosure of a suitable type of propeller for use with the control of this application. As this type of propeller is now well known, further detailed description thereof is believed to be unnecessary.

Hydraulic fluid is led from the control mechanism to the propeller through the conduits 42 and 44 in the propeller hub. Conduit 42 leading into the hub outside of propeller shaft 46 and through suitable connections such as shown in Patent No. 2,477,868, is led to the forward side of piston 32. Fluid may also be led through conduit 44 in the hub to the interior of the propeller hub and the space to the rear or inboard side of piston 32. Suitable means such as a gasket 48 prevents flow of oil inboard along the propeller shaft, the propeller surrounding the outboard end of the propeller shaft closes the outboard end against the loss of oil in the outboard direction. Oil from the control mechanism is directed into a groove 54 on the inside of sleeve 14, which when assembled on hub projection 16, is in hydraulic communication with conduit 42. Oil may also be led from the control unit into groove 60 formed in the interior of bearing sleeve 14. Groove 60, when assembled on the hub projection 16, is in hydraulic communication with the conduit 44.

The control unit 10 comprises a main casting 74 which supports all of the various control elements, including the governor valve indicated generally at 76, the scavenge pump, indicated generally at 78, the main pump and its connections indicated generally at 80, the auxiliary pump and motor indicated generally at 82, the various valves and their controls, to which reference will be made hereinafter, and the oil reservoir, indicated generally at 84. The various control elements are preferably separate units bolted or otherwise removably secured to the main casting. A bearing sleeve 86 is secured in main casting 74 and serves to rotatably support the entire control system on the bearing sleeve 14 which is secured as previously described on the hub projection 16. Bearing sleeve 86 is provided with a bearing metal such as babbitt on its inner diameter and inboard face which provides a bearing surface cooperating with the outer surface of bearing sleeve 14 to provide a suitable running joint between the stationary control unit and the rotating propeller unit.

Four grooves 88, 90, 92 and 94 are provided in the outer surface of bearing sleeve 86 and, like the grooves in the interior of sleeve 14, are prevented from leaking by means of suitable O ring gaskets. Suitable passages lead from groove 94 through sleeve 86 and other passages lead from groove 88 through sleeve 86. Suitable passages lead from grooves 88 and 94 to the governor valve which being thus connected with the propeller pitch changing mechanism controls the flow of oil to and from the pitch changing mechanism. The main and auxiliary pumps are connected in parallel and their output is led to groove 92. Various passages in the main casting connect with groove 92 to deliver the output of the main and auxiliary pumps to the low pressure relief valve, indicated generally at 96, high pressure relief valve, indicated generally at 98, and to the governor valve 100. A passage 102 connects the auxiliary pump 104, driven by auxiliary motor 106 with passage 92. As will be explained later, this auxiliary pump and motor are used to provide pressure fluid to assist the main pump, and also to provide pressure fluid when the propeller is not rotating and the main pump is consequently idle.

Suitable check valves 354, 356 are placed in the output line of the auxiliary and main pumps to assist in preventing bleeding of oil through these pumps when they are idle or otherwise inoperative.

A main sump or reservoir is formed at one side of the main casting 74 of the control unit which is the lower side when the control unit is in its normal upright position, by means of a curved, trough-like cover 108 secured to the lower portion of main casting 74. The main pump 80 is enclosed by the cover 108 and comprises a gear pump 116 driven through gear 118 by a gear 120 formed on an upstanding flange 122 on the inboard side of sleeve 14 secured to rotate with the propeller. Pump 116 has an inlet 124 located near the bottom of the reservoir. This inlet, however, is spaced from the bottom of the reservoir a greater distance than inlet 126 leading to auxiliary pump 104 so that in the event of failure of the propeller to change pitch due to lack of oil it may still be possible to feather the propeller by means of the auxiliary motor which can still pump oil if the lack of oil is caused by the level falling just below the inlet to the main pump.

As stated above, oil from main pump 116 is led to passage 92 and thence to the governor valve 100 from where it is directed in the usual manner by the governor to the proper side of the pitch changing motor to maintain constant propeller speed by varying the propeller pitch. The governor is driven from gear 120 by gear 136 and a pair of bevel gears as shown in Fig. 2. The governor comprises the usual flyweights 140 opposed by a speeder spring whose tension may be adjusted in a well known manner from the pilot's cockpit. Pressure oil is also led through passage 144 to solenoid actuated feathering valve 146 and solenoid actuated reversing valve 148 which are normally closed. Actuation of the feathering valve will direct pressure fluid through conduit 150 to the underside piston 152 on the lower side of governor valve 100 to thereby raise the governor valve 100 and connect pressure fluid with groove 88 and the pitch increasing side of the piston 32 of the pitch changing motor.

Actuation of the reversing valve will direct pressure fluid from the passage 144 to passage 154 leading to a piston 155 on the top of the governor valve 100 thereby forcing the pilot valve down to direct pressure fluid from groove 92 into groove 94 and thence to the pitch reducing side of the piston 32 in the pitch changing motor.

Pressure oil is also led from the passage 92 to the front face of plunger 156 of relief valve 96 which is urged into closed position by spring 158. The relief setting of relief valve 96 is normally determined by the capacity of spring 158 but may be increased by leading oil under pressure to the backside of plunger 156. This is accomplished by a shuttle valve 160, one side of which is connected with the reversing valve 148 and piston 155 on the governor valve 100 and the other side of which is connected with the groove 88 leading to the pitch increasing side of the pitch changing motor. Hence, whenever the reversing valve is opened or whenever pressure fluid is being led to the pitch increasing side of the pitch changing motor, the capacity of the relief valve 96 is increased to thereby increase the pressure output of the main pump. Shuttle valve 160 moves under the predominant pressure acting thereon to connect that predominant pressure with the rear of the plunger 156.

Groove 92 is also connected with a high pressure relief valve 98 which serves to limit the ultimate pressure attainable by the main pump. Both relief valve 96 and 98 discharge directly into the main sump or reservoir, relief valve 96 discharging through conduit 161.

Gears 162 of scavenge pump 78 are driven by gear 120 and serve to remove oil that may collect in the drainage area 166 and force it into the reservoir 84 to keep the drainage area free from an accumulation of oil

and maintain reservoir 84 under a pressure determined by the reservoir relief valve indicated generally at 170. Pump 78 may pump both oil and air to maintain the reservoir pressure.

The main casting 74 has projections 186 extending from one side thereof and forming a slot between them. A lug fixed on the engine nose extends to a position between said projections and acts to prevent rotation of the control unit with the propeller while permitting it to move axially and radially with the propeller.

In normal constant speed operation the governor 76 operating valve 100 controls the flow of oil through passages 42, 88, 44 and 94 to maintain constant propeller speed by varying the propeller pitch. Shuttle valve 160 is maintained in the position shown in Figure 1 to apply pressure back of relief valve plunger 156 whenever pressure oil is introduced to the pitch increasing side of the pitch changing motor, scavenging pump 162 serving to keep drainage area 166 free from the accumulation of oil and to maintain a predetermined pressure in reservoir 84.

It has been customary to utilize continuously rotating pumps such as main pump 80 to supply all the hydraulic fluid for changing pitch during constant speed operations. During the major portion of the constant speed operation, only a small quantity of hydraulic fluid is required but during extreme operations such as rapid throttle changes, the entire capacity of the main pump is utilized. Hence the main pump had to be large enough to supply fluid at a rate sufficient to provide the rapid pitch change necessary for these extreme operations. Hence, during the major portion of the time the main pump was pumping an excess of fluid which caused undue heating and a waste of power.

In the present invention applicant has provided means by which the normally stationary auxiliary pump 104 may be utilized to assist the main pump during extreme operations thus permitting a material reduction in the size of the main pump with a consequent reduction of power required and a reduction in the resultant heat of the oil.

A normally open switch 351 having contacts mounted on spring arms is mounted in the governor housing in a position to be actuated by the rod 352 which in turn is actuated by the pilot valve 100 whenever the governor exceeds a preselected overspeed condition. The rod 352 may be suspended in the switch housing and normally spaced at its lower end from the governor valve 100 or it may be constructed as shown as an integral extension of the valve 100. The upward movement of the valve 100 thus serves to close the switch 351. Closing of the switch 351 will energize hold-in coil 311 and energize the auxiliary motor to start the auxiliary pump 104 and assist the main pump 116, thus supplying the additional fluid necessary to give a pitch change rapid enough to avoid any excessive overspeeding.

In general, it is not necessary to have as rapid a pitch reduction as a pitch increase as the underspeeding which will call for a pitch reduction does not produce dangerous conditions. However, if desired, another switch could be provided as shown in Fig. 3 which would be actuated by the governor valve when it approaches its extreme underspeed position which switch could be placed in parallel with switch 351 to energize the auxiliary motor 106 and operate the pump 104 to assist the main pump 116 in pitch reducing movements.

The above mechanism connected with the auxiliary motor 106 does not interfere with the utilization of this auxiliary motor for feathering, unfeathering and, if desired, reversing and unreversing operations as will be explained below.

When it is desired to feather the propeller, feather button 192 in the control compartment of the airplane is pushed to close contacts 194, 196, 198, 200 to thereby energize holding coil 202, to thereby hold feather button

192 depressed. This will also open feathering valve 146, energize feathering solenoid 204 and holding coil 311 closing switch 313 for auxiliary pump motor 106, and operate auxiliary pump 104 to supply fluid in addition to that being supplied by the main pump and to, if necessary, continue to supply fluid after the main pump has ceased operation due to stopping of the propeller. Holding coil 202 is in series with a cut-out switch 206 which is actuated by the pressure fluid changing the propeller pitch. Opening of feathering valve 146 allows pressure fluid from grooves 92 and passage 144 to enter conduit 150 and act on the underside of piston 152 to lift governor valve 100 which will direct fluid from the groove 92 to groove 88 and the pitch increasing side of the pitch changing motor. Lifting of the governor valve 100 by the piston 152 will actuate rod 352 to close switch 351 and provide a second path for electricity for hold-in coil 311 for auxiliary pump switch 313. Pressure oil in groove 88 will move shuttle valve 160 to the position shown to put pressure oil back of plunger 156 of relief valve 96 and will move shuttle valve 208 from the position shown to the lower end of its cylinder to thereby connect the pressure cut-out switch with the pitch increasing side of the pitch changing motor. When the pitch changing motor has reached its limit of movement determined by stops, not shown, the pressure at the pitch increasing side of the pitch changing motor will increase creating a pressure surge which will open the pressure cut-out switch releasing the holding coil 202 and permitting springs 300 to return the feather button 192 to its off position as shown in Figure 1. Return of the feather button 192 to its off position will break the circuit through contact 200 to hold-in coil 311 and will break the circuit through contact 198 to the feathering solenoid 204 thus permitting the governor to return under the influence of the speeder spring to an underspeed condition thus opening switch 351 to de-energize hold-in coil 311 thus stopping the auxiliary motor.

To unfeather the propeller from its non-rotating feathered position, button 192 is pulled to the left as viewed in Figure 1, closing contacts 302, 304, 306 and 308 to thereby energize holding coil 310 closing switches 318 and 318a, energizing holding coil 311 and consequently energizing auxiliary pump motor 106 and reversing solenoid 312 thus opening reversing valve 148. Operation of auxiliary pump motor 106 will supply auxiliary fluid in the same manner as described for feathering, except that it must supply all the fluid at the beginning of the operation as the main pump 116 then does not operate and it will assist the main pump after the propeller starts to rotate. Opening of reversing valve 148 will allow pressure fluid from groove 92 and passage 144 to enter passage 154 and act on the upper surface of piston 155 to thereby force the governor valve 100 down and admit pressure fluid from groove 92 to 94 and hence to the pitch decreasing side of the pitch changing motor. Pressure fluid in passage 154 will move shuttle valve 160 to apply pressure fluid back of plunger 156 of relief valve 96 to thereby increase the available pressure. Pressure in groove 94 will move shuttle valve 208 to the position shown in Fig. 1 thereby connecting the pitch decreasing side of the pitch changing motor with the pressure cut-out switch 206. The pressure cut-out switch, however, is not utilized to stop the unfeathering operation as this is accomplished by electrical contacts on the propeller blade shank. When the propeller blade has reached a predetermined position in its pitch reducing movement the current in holding coil 310 is broken by an insulating segment 314 thus releasing holding coil 310 allowing spring 316 to return switch 318 to an off or neutral position thus breaking the current to reversing solenoid 312 and auxiliary motor 106. The plunger which cooperates with holding coil 202 is so far out of the holding coil when button 192 is in unfeather position that holding coil 202 has no affect. Button 192 is held out manually for

unfeathering and may be released at any time after the propeller starts windmilling. If, however, it is not released by the time the propeller has reduced its pitch well into the operating range, the reversing solenoid and the auxiliary motor will be de-energized by the breaking of the circuit of the holding coil 310 by insulating segment 314 at which time the governor will take over control. As in the feathering operation the switch is returned to its neutral position by springs 300 after it is released. Reference may be had to application Serial No. 32,244 of Martin and McCarthy, filed June 10, 1948 for a more complete description of the construction and operation of the insulating and conducting segments on the blade 18. It will be sufficient to state here that by means of a brush, insulated from, and held in fixed position on the propeller hub an electric circuit may be completed by being conducted to ground through conducting segments 328 and 330 and the propeller blade and hub. The brush and segments are arranged so that the brush will be approximately at the position indicated by F when the propeller is feathered at the position indicated by L. P. when the propeller is at its low pitch stops and at R when the propeller is in its reversed pitch position. It will thus be apparent that even if switch knob 192 is held in the unfeather position when conducting segment 330 contacts the brush, the circuit will again be broken by insulating segment 332 before the propeller reaches its low pitch stop. This will prevent the propeller from going into reverse pitch while unfeathering because the pressure level maintained by relief valve 96 alone, when not backed up by pressure from reversing valve 148, is not sufficient to overcome the low pitch stops.

In order to reverse the propeller pitch, switch 320 is first closed and then reverse-unreverse switch 322 is moved into the reverse position which is the lower position as viewed in Figure 1. Closing of these switches will energize reversing solenoid 312 and holding coils 324 and 326. Energizing holding coil 324 will close switches 334 and 336. Closing switch 334 will effect short circuit switch 322 so as to maintain holding coils 324 and 326 energized independent of the position of switch 322. Energizing holding coil 326 will close switch 338 which will in effect short circuit switch 320 so as to maintain holding coils 324, 326 energized independent of the position of switch 320. Energizing holding coil 326 will also close switch 354 to start the auxiliary pump in operation. The closing of switch 336 has no immediate effect, but prepares the circuit for unreversing which will be described later. After passing through switches 320, 322 and holding coils 324, 326 the current passes through switch 340 to ground. Switch 340 is normally held closed by spring 342. Energizing the reversing solenoid 312 will produce the same hydraulic action as in unfeathering. As in unfeathering, governor valve 100 is forced down so as to connect groove 92 with groove 94 and direct fluid to the pitch reducing side of the pitch changing motor. It is to be understood that as is usual in this double acting type of control, each time pressure fluid is conducted to one side of the pitch changing motor, the opposite side of the motor is connected to drain or the reservoir to permit fluid to flow from one side of the motor as it is introduced to the other side. Switches 320 and 322 remain in the closed position just described as long as it is desired to have the propeller remain in the reversed pitch position and the propeller is maintained in that position by the fluid from the main pump and the auxiliary pump being continuously directed to the pitch reducing side of the pitch changing motor, thereby forcing the propeller against the reverse pitch or pitch limiting stops not shown. If the reversing operation is to be continued for any appreciable length of time, it may be desirable to disconnect the auxiliary pump and allow the propeller to be held in reverse pitch by the main pump alone. This can be accomplished by inserting a switch 356 in the line between the switch 354 and the auxiliary motor 106 which switch may

be manually operated or if desired may be automatically operated by a mechanism such as a second blade switch similar to that illustrated or a timing mechanism.

To unreverse the propeller and bring it back into the constant speed range, switch 322 is first changed from its reversed to its unreversed position, the position shown in Figure 1, which will de-energize solenoid 312 and close valve 148. In the unreversed position of switch 322 the current will be conducted through switch 336 which is still maintained closed by holding coil 324 and will energize feathering, or increase pitch, solenoid 204. Switch 320 is then opened, but as it short circuited by switch 338, it has no immediate effect. Placing switch 322 in the unreverse position will also close a circuit to prepare holding coil 344 for action when the circuit is completed through contact 330. Energizing increase pitch solenoid 204 will cause actuation of the governor valve 100 in the same manner as was described in the feathering operation closing switch 351 to energize the auxiliary pump and motor. The governor valve 100 is moved to connect groove 92 with groove 88 and apply pressure fluid to the pitch increasing side of the pitch changing motor and thus move the blades 18 from reverse pitch through zero pitch to increased pitch position. After the blade pitch has been increased to a pitch somewhat above the pitch defined by the low pitch stops, brush 346 will make contact with conducting segment 330, which will energize holding coil 344 to thereby open switch 340. Opening switch 340 will break the ground connection of holding coils 324 and 326 thus de-energizing them. Springs 348 and 350 will now open switches 334 and 338 and de-energize increase pitch solenoid 204, closing valve 146 and thus opening switch 351 and returning the governor valve 100 to governor control.

As has been indicated above, the switch actuated by the rod 352 may be arranged so as to be actuated both when the governor reaches a selected overspeed position and when it reaches a selected underspeed position. Fig. 3 illustrates a wiring diagram showing how such a switch may be fitted into the above-described structure. The rod 352 is attached to the pilot valve 100 for actuation in both directions in accordance with the position of the pilot valve. As in the single switch of Fig. 1, there may be lost motion provided between the governor valve 100 and the rod 352, or the lost motion may be between the rod and the switch or even in the switch itself. A lost motion equivalent to 50 R. P. M. above and 50 R. P. M. below the on-speed position has been found to be satisfactory. Shoulders 360 and 362 on the rod 352 are effective to acuate the switches upon movement of the rod. Upward movement of the rod 352 will cause shoulder 360 to close switch 351 and operate the auxiliary motor 106 as described above. Shoulder 362 will be moved downward on underspeed and when the governor reaches a selected underspeed condition will close the switch 364 to energize line 366. A switch 368 connects line 366 with holding coil 311 to close switch 313 and acuate the auxiliary motor 106. Switch 368 is closed by a solenoid holding coil 370 which is controlled by a blade switch 372 mounted on one of the propeller blades 40. Blade switch 372 has a conducting portion 374 which will keep holding coil 370 energized and switch 368 closed except near the reverse and feathered positions where insulating segments 376 and 380 will break the circuit through hold-in coil 370 allowing switch 368 to open. Hence, during the normal operating range, whenever the propeller reaches a preselected underspeed condition, switch 364 will close and switch 368 will operate the auxiliary motor 106. Line 366 is also connected through switch 318a to the hold-in coil 311 so that, when the propeller reaches a feathered position and stops rotating, thus causing the the governor to stop rotating, and assume an underspeed position closing switch 364, although switch 364 will be closed, it will not operate the auxiliary motor 106 because both switch 318a and 368 will be open.

When it is desired to unfeather, button 192 is pulled to the unfeathered position energizing hold-in coil 310, closing the switch 318a and completing the circuit through switch 364 to the hold-in coil 311 and thus energizing the auxiliary motor 106. The connection between contact 308 and switch 318a may be allowed to remain as shown in Fig. 1, in addition to the connection shown in Fig. 3, giving two parallel connections to coil 311 or the connection of line 366 with switch 318a may replace the connection between contact 308 and switch 318a. The connection between contact 308 and coil 310 will of course remain as shown in Fig. 1. In feathering the propeller the connections between contact 209 and the holding coil 311 may be allowed to remain as shown in Fig. 1 or may be removed relying entirely upon the closing of switch 351 by the movement of the governor incident to operation of the feathering solenoid if desired. It will of course be apparent that operation of the feathering solenoid 204 will, through the resulting movement of pilot valve 100, close switch 351. Operation of the reversing solenoid 312 will, through the resulting action of the governor valve 100, close switch 364, which switches 351 and 364 can be utilized for the feathering and reversing actions.

In reversing, actuation of reversing solenoid 312 by placing switch 322 in reverse position will close switch 364 and, switch 368 being closed, will acuate the auxiliary motor to assist in reversing. Just before the reverse pitch position is reached, insulating segment 376 will come under brush 346 to de-energize coil 370 and allow its spring to open switch 368 to stop the auxiliary motor 106. The propeller may then be held in reverse pitch position through the action of the reversing solenoid 312 by main pump 116.

In unreversing, the feathering solenoid 204 actuated by moving switch 322 to unreverse position will act to move the governor to close switch 351 and energize coil 311 energizing the auxiliary motor. The de-energization of the feathering solenoid 204 by the opening of switch 336 when coil 344 is energized through contact 330 to open switch 340 and break the ground to coil 324, will of course release the governor to open switch 351 when the propeller speed returns to within 50 R. P. M. of the governor speed setting and the propeller will be returned to governor control. It will be apparent that the governor actuated switches 351 and 364 can be utilized not only for boosting oil flow during governor control but may also be used in the operations outside of the governor range for feathering, unfeathering, reversing and unreversing.

If desired, contact strip 374 may be shortened so as to extend from adjacent the reverse position to only slightly beyond the low pitch position in the governor range so as to limit the use of the auxiliary motor to pitch increasing movements during governor operations. The switch 368 being open in the governing and feathering ranges and being closed only in the reverse range, and switch 318a being closed only in the unfeathering operation, the switch 364 will not be effective to energize the auxiliary motor for pitch reduction in the governing range. Use of switch 364 in operating the auxiliary motor 106 for pitch reduction would therefore be limited to reversing and to unfeathering.

The propeller has been described in connection with a pressure cut-out switch 206 but if desired a suitable timing mechanism may be substituted for the cut-out switch which mechanism instead of operating on a pressure surge, will operate to disconnect the auxiliary motor after a predetermined elapsed time.

The timer may be used to measure the elapsed time from the time energy is supplied to the auxiliary motor for feathering and may also be used to measure the elapsed time from the supplying of energy to the auxiliary motor for reversing, being substituted for the cut-out

switch in the first instance and for the manually actuated switch 356 in the second instance.

It is to be understood that the invention is not limited to the specific embodiment herein illustrated and described, but may be used in other ways without departure from its spirit as defined by the following claims.

I claim:

1. In combination with a hydraulic governor having a valve controlling the flow of fluid from a source of fluid pressure to a device to be controlled, an auxiliary source of fluid pressure, a conduit connecting said auxiliary source with said governor valve, a check valve in said conduit preventing flow from said governor valve toward said auxiliary source, said conduit being continuously open for flow from said auxiliary source to said governor valve, means actuated by said governor valve, when, in its governing operation, it reaches a predetermined off-speed position, for supplying additional fluid from said auxiliary source to said governor valve in parallel with said first mentioned source.

2. A device as claimed in claim 1 including means for de-energizing said auxiliary source while the governor is on speed or within a predetermined amount of off speed.

3. A control for an adjustable pitch propeller comprising, a continuously operating fluid pump, an outlet for said control, a speed responsive governor controlling the flow of fluid from said pump to said outlet, a normally inactive fluid pump connected in parallel with said continuously operating pump, means actuated by said governor, when in its governing operation it reaches a predetermined off speed position, including means for actuating said inactive pump, for supplying fluid to said outlet.

4. A control for an adjustable pitch propeller comprising, a fluid pump actuated by rotation of said propeller, a speed responsive governor controlling the flow of fluid from said pump to said propeller to control the pitch thereof, a source of fluid pressure connected in parallel with said pump, an electric switch, means connected with said governor for actuating said switch when the governor in its governing operation reaches a predetermined off speed position, and means responsive to operation of said switch for energizing said source to supply fluid from said source to said propeller.

5. A device as claimed in claim 4 in which the means responsive to operation of said switch includes an electric motor and a pump actuated thereby.

6. A control for a hydraulically actuated controllable pitch propeller having a fluid reservoir and a pump connected with said reservoir for drawing fluid therefrom and continuously operated by rotation of said propeller for continuously supplying hydraulic actuating fluid under pressure during operation of said propeller, a governor for controlling the application of said fluid to said propeller for controlling the pitch thereof, a second normally inactive pump connected with said reservoir for drawing fluid therefrom, and means connected with said second pump and actuated by said governor when it reaches a selected off speed position in its governing operation to actuate said second pump and supply fluid in parallel with said continuously operating pump.

7. In combination with a feathering type controllable pitch propeller having means for supplying fluid from a first source of fluid pressure for feathering and unfeathering said propeller independent of propeller rotation, a governor for said propeller, a second source of fluid under pressure, means for supplying fluid from said second source through said governor to said propeller during normal governed speed operation, and means responsive to a selected off speed condition of said propeller for automatically supplying additional fluid under pressure during governed operation from said feathering and unfeathering supply.

8. A device as claimed in claim 7 in which said first source of fluid pressure comprises an electrically driven

pump and the means responsive to a selected off speed condition includes a switch actuated by said governor.

9. A device as claimed in claim 8 in which said second source of fluid under pressure includes a pump operated continuously by rotation of said propeller and the propeller includes a common sump for both pumps.

10. A device as claimed in claim 8 including a manually actuated switch for controlling said source of fluid pressure for feathering and unfeathering connected in parallel with said governor actuated switch.

11. A hydraulic governor having a reciprocating valve for controlling fluid flow, switch means actuatable by said valve adjacent the limit of its reciprocation, a normally de-energized source of fluid pressure connected with said governor and controlled by said switch, said valve being movable incident to the governing action of said governor to actuate said switch and energize said source and manually controlled means for moving said valve to actuate said switch and energize said source.

12. In combination with a controllable pitch propeller, a first source of fluid pressure energized by rotation of said propeller, a governor valve controlling the application of said fluid to said propeller, a second source of fluid pressure independent of rotation of said propeller, connected in parallel with said first source, means actuated by said governor valve when it reaches a predetermined offspeed position for supplying fluid from said second source to assist said first source in governing said propeller.

13. A governor, driving means for said governor, a main pump continuously driven by said governor driving means, means continuously directing the output of said pump to said governor, a second pump, driving means for said second pump independent of said main pump driving means, means including a check valve connecting the outlets of said pumps, said check valve preventing flow from said main pump to said second pump and opened by an excess of pressure from said second pump over the pressure of said main pump and connecting said second pump with said governor in parallel with said first pump and means controlled by said governor controlling said second pump driving means.

14. A device as claimed in claim 13 wherein said governor controlled means includes switch means connected with said governor and actuated thereby for controlling the operation of said second pump driving means.

15. In combination, an engine driven hydraulically actuated controllable pitch propeller, a main pump continuously actuated by rotation of said propeller, a governor valve having an onspeed position and offspeed positions, means connecting said pump with said valve and means connecting said valve with said propeller, said governor valve controlling the flow of fluid between said pump and said propeller to vary the propeller pitch and control the engine speed, a second normally inoperative pump, electric motor means for operating said second pump, a switch connected with said electric motor, means connected with said governor for actuating said switch to energize said motor when the governor, while governing, reaches a predetermined offspeed condition, means connecting said second pump with said valve in parallel with said main pump.

16. Governor control means for a controllable pitch propeller comprising a governor valve for directing fluid under pressure to said propeller, a normally de-energized electrically driven pump for supplying fluid under pressure to said valve, governor actuated switches for energizing said pump, means connected with said governor for closing one of said switches and energizing said pump when the governor reaches a predetermined overspeed condition, and closing another of said switches and energizing said pump when the governor reaches a predetermined underspeed condition, and additional means for supplying fluid to said governor for governing said propeller between said offspeed conditions.

17. In combination with a governor having an onspeed

position and having governor-controlled electrically-actuated means for supplying speed correcting forces on opposite sides of said onspeed position, said governor having a dead band at and adjacent the onspeed position of said governor in which said electrically actuated means are inoperative, and means controlled by said governor for supplying speed correcting forces in said dead band independent of said electrically actuated means.

18. In combination with a controllable pitch propeller, a first source of fluid pressure energized by rotation of said propeller, a governor controlling the application of said fluid to said propeller, a second source of fluid pressure independent of rotation of said propeller, connected in parallel with said first source, means actuated by said governor when it reaches a predetermined off-speed position or supplying fluid from said second source to assist said first source in governing said propeller, manually controlled mechanism for disabling the governing function of said governor by setting the governor in an offspeed position, independent of propeller speed, said manually set governor directing the application of fluid to said propeller for moving the propeller out of governing range into a special purpose range and actuating said means actuatable by said governor to supply fluid to move said propeller in said special purpose range.

19. Control means for a controllable pitch propeller having a governed range of pitch change and a special

purpose range outside of said governed range, comprising a source of energy, a speed responsive governor controlling the application of said energy to said propeller for controlling the pitch changing movements of said propeller in the governed range, a second source of energy for actuating said propeller in said special purpose range when the propeller is not rotating, means actuated by said governor in its governing action when it reaches a predetermined offspeed position for controlling the supply of energy from said second source to said propeller in parallel with said first source, means for disabling said governor and moving it to one extreme limit of its travel to actuate said governor actuated means and supply energy from said second source for moving said propeller in said special purpose range.
